US00D584130S

(12) **United States Design Patent**
Bertani

(10) **Patent No.:** **US D584,130 S**
(45) **Date of Patent:** **** Jan. 6, 2009**

(54) **HINGE**

(75) Inventor: **Alberto Bertani**, Milan (IT)

(73) Assignee: **Elesa S.p.A.**, Milan (IT)

(**) Term: **14 Years**

(21) Appl. No.: **29/317,475**

(22) Filed: **Apr. 30, 2008**

(30) **Foreign Application Priority Data**

Oct. 31, 2007 (EM) 000818356

(51) **LOC (9) Cl.** **08-06**

(52) **U.S. Cl.** **D8/328**

(58) **Field of Classification Search** D8/323-329,
D8/354, 356; 16/234-237, 239-241, 245,
16/246, 249, 254, 261, 262, 265, 272, 277,
16/307, 309, 316, 319, 335, 338, 339, 342,
16/379-389, 221; 248/200, 211.11, 300,
248/309.1, 317; 4/236-240

See application file for complete search history.
